CLAIM

The ornamental design of a medical diagnostic kit, as shown.

DESCRIPTION

FIG. 1 is a front perspective view of a medical diagnostic kit in accordance with our new design;

FIG. 2 is a front elevation view thereof;

FIG. 3 is a rear elevation view thereof;

FIG. 4 is a side view thereof;

FIG. 5 is a side view thereof, for the side opposite that of FIG. 4;

FIG. 6 is a top view thereof;

FIG. 7 is a bottom view thereof; and,

FIG. 8 is a rear perspective view thereof.

The broken lines shown in the drawings illustrate portions of the medical diagnostic kit that form no part of the claimed design.

1 Claim, 5 Drawing Sheets
